UNITED STATES PATENT OFFICE.

GEORGE ALBERT LYON, OF PHILADELPHIA, PENNSYLVANIA.

AUTOMOBILE-BUFFER.

1,325,737.

Specification of Letters Patent. Patented Dec. 23, 1919.

Application filed May 25, 1918. Serial No. 236,513.

To all whom it may concern:
Be it known that I, GEORGE ALBERT LYON, a citizen of the United States, and resident of Philadelphia, Philadelphia county, State 5 of Pennsylvania, have made a certain new and useful Invention Relating to Automobile-Buffers, of which the following is a specification, taken in connection with the accompanying drawing, which forms part 10 of the same.

This invention relates especially to resilient or spring strip buffers for use on Ford or similar automobiles or other vehicles, the rearwardly extending attaching members 15 of the buffer being oppositely inclined or bent into reinforcing diagonal position so that they are considerably stiffened against lateral vibration and movement without losing their vertical rigidity to an undesirable extent. These attaching members may have rearward anchoring extensions formed integral therewith so as to 20 extend a considerable distance backward along the frame members to which they may be secured in any suitable way as by bolting an inturned end of such anchoring extension to the frame where the usual drip pan bolt is located on the Ford automobile. These diagonal attaching members are not 25 only stiffer and stronger against lateral vibration and collision impact, but they may, if desired, be clamped substantially flat against the inclined lamp brackets so as to give a rigid and strong attachment for the buffer members. These attaching members 30 may have forwardly and outwardly curved portions at their front ends which may be provided with resilient looped ends to be bolted or otherwise connected to the buffer front or impact receiving portion which may 35 be formed of one or more spring strips which may be forwardly bowed in substantially uniformly curved shape, if desired, and these spring strips may overlap and reinforce each other adjacent the middle of 40 the buffer and be bolted or otherwise connected at these portions.

In the accompanying drawing showing in a somewhat diagrammatic way illustrative embodiments of the invention. 45

Figure 1 is a perspective view showing one form of the buffer attached to a Ford automobile, parts of which are shown in dotted lines.

Fig. 2 is an enlarged transverse section 55 taken through one of the attaching members of the buffer.

Fig. 3 is a plan view of the buffer.

Fig. 4 shows the buffer when disconnected and arranged for shipping. 60

Fig. 5 is a plan view showing another form of buffer; and

Fig. 6 is a partial plan view showing still another embodiment.

The front or impact receiving member 65 of the buffer may be of any suitable form or construction and it may advantageously be formed of a plurality of more or less overlapping spring strips such as 29, 30, which as indicated in Fig. 3 may be forwardly bowed and may have substantially uniform curvature so as to give a pleasing appearance to the finished buffer and allow lateral adjustment of these impact receiving members when it is desired to have a 70 buffer of adjustable width to fit different width vehicle frames. Any suitable connecting means may be used to connect these front members preferably in a vertically rigid manner and at the same time effecting 75 the desired lateral adjustment of these spring strips when the buffer is to be used on different automobiles. For a Ford automobile, buffer connector bolts, such as 22, may be conveniently used which may have 80 a convex or boss-shaped head projecting from the forward face of the buffer front member and may extend through holes or connecting apertures, such as 23, in the spring strips 29, 30. If desired these bolts 85 may be formed with square polygonal or other non-circular shanks, such as 21, to fit within corresponding holes in one or both of the spring strips which may be tightly connected as by screwing home the nuts 90 24 on these bolts in connection with suitable lock washers, if desired.

The spring strip attaching members 5, 6 may have forwardly and outwardly curved portions bolted or otherwise connected to 100 the ends of the impact receiving members and either one of these two sets of members may be formed with a resilient end loop portion to increase the resilience of the buffer. If desired these resilient end loops, 105 such as 31, may be formed on the ends of the impact receiving members which gives a pleasing appearance to the buffer and at

the same time increases its resilient yielding action under collision conditions. The end loops may terminate in connector portions, such as 38, which may extend substantially 5 parallel to the adjacent front portion of the corresponding impact receiving member. Coöperating connector portions, such as 8, may be formed on the attaching members so as to fit against and be strongly and 10 rigidly secured to the connector portions of the impact receiving members when clamped or bolted thereto in any suitable way. U-bolt attaching connectors, such as 16, are desirable for this purpose and as indicated 15 they may extend through suitable holes 26 in the coöperating connector portions of these spring strip members so as to not only frictionally hold them together, but to maintain them in substantial vertical alinement 20 when the nuts 18 on the bolt shanks are screwed down on the lock washers 17, for example. In order to secure greater lateral rigidity in these attaching members they may with advantage have their rearwardly 25 extending portions oppositely vertically inclined or bent about their axes into diagonal position so as to mutually reinforce and stiffen this part of the buffer against lateral vibration or yielding, while at the same 30 time sufficient vertical rigidity is retained in these spring strips so that they are not undesirably weakened against vertical running vibration. It is desirable to have the front ends of these attaching members substantially 35 vertical adjacent the impact receiving portions of the buffer and from this point the inclination may gradually increase, as is shown in Fig. 3, until the substantially straight rearwardly extending 40 parts of these attaching members 5, 6, may be oppositely inclined at about 45 degrees or so as is indicated in Fig. 2.

In some cases these attaching members may be extended to a greater or less degree 45 to form anchoring extensions which may be conveniently bolted directly to the vehicle frame at a considerable distance back of the radiator or front portion of the frame in some instances. With the ordinary Ford 50 automobile the frame members 4 are substantially straight up to about the front of the hood 1, as is indicated in Fig. 1, and the drip pan 28 is usually bolted to the bottom flange of each of these frame members by 55 suitable bolts, such as 12, see Fig. 2. The lamp brackets 2, 3 bolted to and extending diagonally out from the frame members adjacent the front of the machine make it 60 difficult to attach a bumper to the frame without special fittings or connections, but this oppositely inclined diagonal stiffening arrangement of the attaching members may be utilized by having such oppositely inclined attaching members lie against and 65 if desired be bolted or clamped to these

inclined lamp brackets near the frame members. For this purpose one or more U-bolt attaching clamps such as 14 may be used adjacent each lamp bracket and if desired may extend through holes punched or otherwise formed in the attaching members 5, 6, so that the nuts 15 together with the lock washers 25, if desired, tightly hold these parts together. The anchoring extensions of the attaching members may be formed 70 with inturned ends 9, 10 having holes through which extend the usual or special pan bolts 12 having, if desired, nuts 11 on the inside of the frame flange. In this way the anchoring extensions are firmly and 75 strongly secured to the frame and the U-bolt attaching clamps provide a rigid and strong connection for the buffer members near the front of the automobile frame so that the impact receiving or front members 80 of the buffer are rigidly and strongly held in protective position in front of the radiator and wheels. The use of U-bolt connectors and attaching clamps is also advantageous in this connection because it furnishes 85 a double security against loosening, the U-bolts still remaining in position if one of the nuts become loosened or even lost. The U-bolt attaching connectors 16 are desirable for this reason and also because they stiffen 90 and aline the two buffer members through which each of these U-bolt connector devices passes at the same time giving a pleasing and finished appearance to the buffer front as indicated in Figs. 1 and 5. As previously 100 indicated the buffer may be readily assembled and clamped to the automobile by practically any garage man or car owner without special tools or instructions and the buffer is composed of such shaped and sized 105 parts as to make a compact shipping package. Fig. 4 indicating one form in which the members may be arranged for this purpose. It is also evident that the buffer elements may be quickly and conveniently bent 110 and fabricated and given the desired spring temper which imparts to them a maximum of strength and resilience to take up a heavy collision impact and protect the automobile.

Fig. 5 shows another form of the buffer 115 in which the buffer front may be formed of one or more impact receiving members of spring strip which may be forwardly bowed. These impact receiving members 19, 20, which may be of uniformly curved forwardly bowed shape may also overlap throughout their central portions between the frame members of the automobile and be similarly clamped together by connector bolts 22. The outwardly projecting ends of 120 these impact receiving members may, if desired, be directly bolted to the connector portions 7, 8 of the attaching members 5, 6, which may be similarly formed and connected to the automobile, if desired. For 125 130

some special purposes the buffer may have its front portion or member formed of an angular or channel iron bumper bar 33, as shown in Fig. 6, and the connector portions 5 7, 8, of the similar spring strip attaching members may extend within the channel bar and be bolted to the inner face of its web 34. For this purpose similar U-bolt attaching connector devices 16 may be used and their 10 shanks may extend through holes 35 stamped or otherwise formed in the bumper bar or impact receiving member which may have its projecting ends bent backward somewhat as indicated in the drawing.

15 This invention has been described in connection with a number of embodiments, forms, proportions, parts, arrangements, materials, methods of connection and use, to the details of which disclosure the invention 20 is not of course to be limited, since what is claimed as new and what is desired to be secured by Letters Patent is set forth in the appended claims.

I claim—

25 1. The automobile buffer adapted for use on Ford or similar automobiles and comprising a resilient buffer front composed of two flat spring strip impact receiving members having overlapping reinforcing portions and 30 provided with connecting apertures, connector bolts extending through said apertures to connect said impact receiving members and hold them against vertical movement, said impact receiving members being 35 substantially uniformly curved and forwardly bowed and being formed with integral resilient end loops having end connector portions substantially parallel to the adjacent front portions of the corresponding 40 impact member, coöperating spring strip attaching members having forwardly and outwardly curved portions and end connector 45 portions shaped to substantially conform to the corresponding end connector portions of the buffer front, connecting apertures formed in said connector portions and U-bolt attaching connectors extending through said apertures to bolt said attaching members to the buffer front, said attaching members having 50 oppositely vertically inclined reinforcing diagonal stiffening portions to the rear of said curved portions and having integral anchoring extensions provided with inturned ends adapted to be bolted beneath the flange 55 frame members and U-bolt attaching clamps passing through holes in said attaching members and adapted to extend around the inclined lamp brackets of the automobile to clamp said inclined attaching members flat 60 against the lower faces of said lamp brackets.

2. The automobile buffer adapted for use on Ford or similar automobiles and comprising a resilient buffer front composed of flat spring strip and being formed with integral resilient end loops having end con-

nector portions substantially parallel to the adjacent front portions, coöperating spring strip attaching members having forwardly and outwardly curved portions and end connector portions shaped to substantially conform to the corresponding end connector portions of the buffer front, connecting apertures formed in said connector portions and U-bolt attaching connectors extending through said apertures to bolt said attaching members to the buffer front, said attaching members having oppositely vertically inclined reinforcing diagonal stiffening portions to the rear of said curved portions and having integral anchoring extensions and U-bolt attaching clamps passing through holes in said attaching members and adapted to extend around the inclined lamp brackets of the automobile to clamp said inclined attaching members flat against the lower faces 70 75 80 85 of said lamp brackets.

3. The automobile buffer adapted for use on Ford or similar automobiles and comprising a resilient buffer front composed of flat spring strip and being formed with integral resilient end loops having end connector portions substantially parallel to the adjacent front portions, coöperating spring strip attaching members having forwardly and outwardly curved portions and end connector portions shaped to substantially conform to the corresponding end connector portions of the buffer front, and attaching connectors extending through apertures to secure said attaching members to the buffer 90 95 front, said attaching members having oppositely vertically inclined reinforcing diagonal stiffening portions to the rear of said curved portions and having integral anchoring extensions and attaching clamps passing through holes in said attaching members and adapted to extend around the inclined lamp brackets of the automobile to clamp said inclined attaching portions flat against the lower faces of said lamp brackets. 100 105 110

4. The automobile buffer adapted for use on Ford or similar automobiles and comprising a resilient buffer front composed of flat spring strip having end connector portions, coöperating spring strip attaching members having forwardly and outwardly extending portions and end connector portions shaped to substantially conform to the adjacent end connector portions of the buffer front, connecting apertures formed in said connector portions and U-bolt attaching connectors extending through said apertures to bolt said attaching members to the buffer front, said attaching members having oppositely vertically inclined reinforcing diagonal stiffening portions to the rear of said outwardly extending portions to clamp said inclined attaching portions flat against the lower faces of the automobile lamp brackets. 115 120 125

5. The automobile buffer adapted for use 130

on Ford or similar automobiles and comprising a buffer front having end connector portions, coöperating spring strip attaching members having forwardly and outwardly extending portions and end connector portions shaped to substantially conform to the adjacent end connector portions of the buffer front, connecting apertures formed in said connector portions and U-bolt attaching connectors extending through said apertures to bolt said attaching members to the buffer front, said attaching members having oppositely vertically inclined stiffening portions to the rear of said outwardly extending portions to clamp said inclined attaching portions flat against the lower faces of the automobile lamp brackets.

6. The automobile buffer adapted for use on Ford or similar automobiles and comprising a buffer front having end connector portions, coöperating spring strip attaching members having forwardly and outwardly extending portions and end connector portions shaped to substantially conform to the adjacent end connector portions of the buffer front, attaching connectors to bolt said attaching members to the buffer front, said attaching members having oppositely vertically inclined stiffening portions to clamp said inclined attaching portions flat against the lower faces of the automobile lamp brackets.

7. The automobile buffer comprising a resilient front portion composed of two flat spring strip impact receiving members having connected overlapping reinforcing portions and having end connector portions, coöperating spring strip attaching members having forwardly and outwardly curved portions and end connector portions coöperating with the connector portions of said impact receiving members, one of said sets of members being formed with integral resilient end loops forming the ends of the buffer front and increasing its resilience, said attaching members having behind said curved portions vertically oppositely inclined reinforcing diagonal stiffening portions to give increased lateral stiffness and having integral anchor extensions provided with inturned ends adapted to be secured to the automobile.

8. The automobile buffer comprising a resilient front portion composed of flat spring strip impact receiving members having connected overlapping reinforcing portions and having end connector portions, coöperating spring strip attaching members having curved portions and end connector portions coöperating with the connector portions of said impact receiving members, one of said sets of members being formed with integral resilient end loops forming the ends of the buffer front and increasing its resilience, said attaching members having oppositely

vertically inclined reinforcing diagonal stiffening portions to give increased lateral stiffness and adapted to be secured to the automobile.

9. The automobile buffer comprising a resilient front portion composed of two flat spring strip impact receiving members having detachably connected overlapping reinforcing portions and having end connector portions, coöperating spring strip attaching members having forwardly and outwardly extending portions and end connector portions coöperating with the connector portions of said impact receiving members, said impact receiving members being formed with integral resilient end loops forming the ends of the buffer front and increasing its resilience, said attaching members having oppositely vertically inclined reinforcing diagonal stiffening portions to give increased lateral stiffness and adapted to be secured to inclined members of the automobile and having integral anchor extensions adapted to be secured to the automobile frame. 70

10. The automobile buffer comprising a resilient front portion composed of spring strip impact receiving members having detachably connected portions and having end connector portions, coöperating spring strip attaching members having forwardly and outwardly extending portions and connector portions coöperating with the connector portions of said impact receiving members, said impact receiving members being formed with integral resilient loops, said attaching members having oppositely vertically inclined reinforcing diagonal stiffening portions to give increased lateral stiffness and adapted to be secured to inclined members 85 of the automobile and having integral anchor extensions adapted to be secured to the automobile frame. 90

11. The automobile buffer comprising a resilient front portion composed of spring strip impact receiving members having detachably connected portions having end connector portions, coöperating spring strip attaching members having forwardly and outwardly extending portions and connector portions coöperating with the connector portions of said impact receiving members, said impact receiving members being formed with integral resilient loops. 100

12. The automobile buffer comprising a resilient front portion composed of spring strip impact receiving members having detachably connected overlapping reinforcing portions and having end connector portions, coöperating spring strip attaching members having forwardly and outwardly extending portions and end connector portions coöperating with the connector portions of said impact receiving members, said impact receiving members being formed with integral resilient loops. 115

integral resilient end loops forming the ends of the buffer front and increasing its resilience.

13. The automobile buffer comprising a resilient front portion composed of two flat spring strip impact receiving members having overlapping reinforcing portions to be detachably connected and having connector portions and coöperating spring strip attaching members having forwardly and outwardly extending portions and connector portions to be detachably connected with the connector portions of said impact receiving members, one of said sets of members being formed with integral resilient loops forming the ends of the buffer front and increasing its resilience.

14. The automobile buffer comprising a resilient front portion composed of spring strip impact receiving members having overlapping reinforcing portions to be detachably connected and having connector portions and coöperating spring strip attaching members having connector portions to be detachably connected with the connector portions of said impact receiving members, one of said sets of members being formed with integral resilient loops.

15. The automobile buffer comprising an impact receiving buffer front composed of flat spring strip and having a reinforcing central portion and integral resilient end loops, coöperating spring strip attaching members having curved portions and connector portions detachably connected to the buffer front, said attaching members having behind said curved portions oppositely vertically inclined reinforcing diagonal stiffening portions to give increased lateral stiffness and adapted to be secured to inclined members of the automobile and having integral anchor extensions provided with inturned ends adapted to be secured to the automobile frame.

16. The automobile buffer comprising an impact receiving buffer front composed of flat spring strip and having a reinforcing central portion, coöperating spring strip attaching members having curved portions and connector portions detachably connected to the buffer front, said attaching members

having oppositely vertically inclined reinforcing diagonal stiffening portions to give increased lateral stiffness and adapted to be secured to inclined members of the automobile. 55

17. The automobile buffer comprising an impact receiving buffer front composed of flat spring strip, coöperating spring strip attaching members having curved portions and connector portions detachably connected to the buffer front, said attaching members having oppositely vertically inclined reinforcing diagonal stiffening portions to give increased lateral stiffness and adapted to be secured to the automobile. 60 65

18. The automobile buffer comprising an impact receiving buffer front, coöperating spring strip attaching members having curved portions and connector portions detachably connected to the buffer front, said attaching members having oppositely vertically inclined reinforcing diagonal stiffening portions to give increased lateral stiffness and adapted to be secured to the automobile. 70 75

19. In automobile buffers an impact receiving buffer front and connected spring strip attaching members adapted to be connected to the automobile to support the buffer front thereon, said attaching members having connector portions adapted to be vertically arranged and connected to said buffer front and having oppositely vertically inclined diagonal stiffening supporting portions to give increased lateral stiffness. 80 85

20. In automobile buffers spring strip attaching members adapted to be connected to the automobile to support the buffer thereon, said attaching members having outwardly extending connector portions adapted to be vertically arranged and connected to the buffer front and having oppositely vertically inclined diagonal stiffening supporting portions having increased lateral stiffness. 90 95

21. In automobile buffers spring strip attaching members adapted to be connected to the automobile to support the buffer therefrom, said attaching members having oppositely vertically inclined stiffening portions having increased lateral stiffness. 100
